UNITED STATES PATENT OFFICE.

WILLIAM COHEN, OF BAYONNE, NEW JERSEY, ASSIGNOR TO ABRAHAM BALINKY,
OF NEW YORK, N. Y.

HAND EMBROIDERY-MACHINE.

1,362,984.

Specification of Letters Patent. Patented Dec. 21, 1920.

Application filed April 28, 1919. Serial No. 293,101.

To all whom it may concern:

Be it known that I, WILLIAM COHEN, a citizen of the United States, and a resident of Bayonne, in the county of Hudson and 5 State of New Jersey, have invented a new and Improved Hand Embroidery-Machine, of which the following is a full, clear, and exact description.

This invention relates to embroidery machines and has for an object to provide an improved construction over the machine shown in my prior Patent No. 1,265,430, issued May 7, 1918.

A further object, more specifically, is to 15 provide an adjustment for the needle so as to take long or short stitches as desired.

A further object is to provide a general re-shaping of certain parts including a removable foot having an appreciably wide 20 base.

Another object of the invention is to provide a hand embroidery machine in which the machine automatically feeds itself forward regardless of the adjustment of the 25 needle or needles as to the length of loop provided and without the assistance of any springs directly acting on the needle or its particular holder.

In the accompanying drawing:

30 Figure 1 is a perspective view of an embroidery machine disclosing an embodiment of the invention.

Fig. 2 is a longitudinal vertical section 35 through the structure shown in Fig. 1.

Fig. 3 is a sectional view similar to Fig. 2, but showing the needle and associate parts in the position occupied at the end of a downward stroke.

Fig. 4 is a view similar to the lower part 40 of Fig. 3, the same having the parts so positioned as to indicate the needle as it is being withdrawn from the cloth preparatory to making a second loop or stitch.

Fig. 5 is a detail perspective view of the 45 foot removed.

In the present invention it is aimed to provide not only the ready adjustment of the length of loop with one or a large number of needles, but to provide for an 50 adjustment of the needle or needles so that the needle or needles may make long or short stitches. In addition it is aimed to arrange the foot so that it will smooth down in a better manner the stitches and hold the

cloth more exactly during the stitching operation.

Referring to the accompanying drawing by numerals, 1 indicates a piece of cloth of any desired kind on which it is desired to provide embroidery of any design. As 60 shown in Figs. 2, 3 and 4 the various loops 2 are arranged on the side of the cloth which is opposite to that engaged by the foot member 3. This results in the embroidery being worked on what is termed 65 the wrong side. The foot member 3 is caused to contact with the cloth 1 when the device is in use, and together with the tubular frame member 4 to which it is firmly connected preferably by friction forms the 70 frame of the machine. In order that the foot member may be rigidly held in position it has a member 5 which encircles part of the frame member 4 and the rear section 75 6 of the foot member has a notch or opening 7 to provide an opening in the frame to accommodate the screws 8 and 9 herein-after fully described. The lower or material engaging part of foot 3 is provided with a solid section 10 of any desired size 80 to smooth out the embroidery and to hold the parts in a better position for receiving the loops. By this construction and arrangement of foot the same will be held rigidly or firmly to the frame member 4, 85 but may be quickly and easily removed. The frame member 4 is preferably square in cross section in order to prevent turning of the parts and to assist in causing the device 90 to operate so as to move in a straight line 95 secured thereto, or formed integral therewith means for supporting spools 11 and 12 of thread, said means being in the nature of a shelf 13 having upstanding pins 14 arranged thereon on which the spools freely rotate. In the drawing two spools are shown, but only one needle 15, but it will be evident that more than one could be used without departing from the spirit of the invention as disclosed in my patent above identified. The needle 15 fits into a suitable socket in the holder 17. This holder has a threaded aperture 18 for receiving a needle clamping screw 9 which extends 105 through a slot or aperture 20 in the downwardly extending rear side of the hollow member or sleeve 21. It will be evident that

when the screw is tightened the needle or needles are clamped firmly in place. In addition a spring 22 surrounds the screw 9 and acts against the head thereof and against the sleeve 21 so as to have a tendency to swing the needle holder 17 and needle 15 on its pivotal support 23 so as to throw the needle forwardly, or away from the back of the foot 3. The needle holder 17 is provided with an extension 24 against which the screw 8 acts, said screw being threaded through sleeve 21 so as to swing the needle holder 17 against the action of spring 22 and thereby position the point or the eye of the needle 15 as desired in order to produce a long or short stitch regardless of the length of the loop.

Slidingly fitted into the sleeve or hollow member 21 is a sliding bar 25 which has riveted, or secured thereto in any desired manner, a thread-gripping member 26 which may be ordinary stiff metal or spring metal as desired, said thread-gripping member being turned over at 27 at the lower end. This turned over end 27 is preferably provided with at least as many apertures 28 as there are needles 15 so as to guide the yarn or thread 29 to the needles. This thread or yarn passes directly from the spools or spool as the case may be and is threaded through the openings in the end 27 as shown in the drawing, or in any desired manner to produce the desired tension in a simple way.

Near the upper part of sliding sleeve 21 and above the frame member 4 is an auxiliary sleeve 30 having a set screw 31 whereby this auxiliary sleeve may be locked in any desired adjusted position for limiting or controlling the length of the loop 2. The extreme upper end of the sliding bar 25 is provided with a handle 32 preferably more or less ornamental so as to give a finished appearance to the machine. When it is desired to lengthen the loop 2 so that the embroidery will be thicker the band or auxiliary sleeve 30 is moved upwardly and locked in the desired position. The distance between the lower end of this sleeve 50 and the upper end of the frame member 4 determines the length of the loop. When it is desired to adjust the position of the needle 15 and thereby the length of the stitch, screw 8 is moved in either direction 55 according to the way the needle is to be moved.

In operation, when the parts are arranged as shown for instance in Figs. 1 and 2 and the thread or threads properly threaded 60 through the openings 28 and the eyes of the needles, the handle 32 is moved up and down. During the up and down movement of this handle the frame member 4 is grasped by one hand while the other hand 65 operates the handle 32. The hand grasping

the frame member 4 naturally steers or guides the foot and the needle over the design to be embroidered. As the needle moves downwardly the inclined position of the needle in its pivotally mounted holder 70 17 acts to feed the device forwardly during each stitch. When the device is ready for use and the needles forced downwardly through the cloth 1 as shown in Fig. 3, the downward and also the upward movement 75 act to force the parts in position as shown in Fig. 4, so that as soon as the needle or needles are withdrawn the spring 22 will act to throw the needles forwardly from the position shown in Fig. 4 to that shown 80 in Figs. 1 and 2.

What I claim is:

1. In a hand embroidering machine, a frame including a foot and a tubular member supported thereby, a sleeve slidable in 85 said member, a needle holder pivoted to said sleeve and having a needle aperture therein, a set screw extending through said sleeve and into said needle holder for retaining a needle in said aperture, a spring 90 surrounding said screw and bearing against its head and said sleeve and a set screw extending through said sleeve and adjustably limiting the swing of said needle holder under the action of said spring.

2. In a hand embroidering machine, a frame comprising a tubular portion and a foot having a part partially encircling and in gripping engagement with said tubular portion and a material engaging part, a 100 member reciprocable in said tubular portion, a needle holder pivoted to said member, a spring movable with said member and tending to swing said holder about its pivot, and an adjusting screw threaded into said member and engaging said holder to adjustably limit its swinging under the action of said spring, said frame having an opening in one side through which said adjusting screw extends for adjustment.

3. In a hand embroidering machine, a foot comprising a vertical portion, a resilient encircling portion carried by one end thereof and a material engaging portion carried by the other end thereof, and a needle operating device positioned within said encircling member, said foot having a notch extending through said encircling member and into said vertical portion whereby the resilience of said vertical portion and encircling member causes said encircling member to grip said needle operating device.

4. In a hand embroidering machine, a frame comprising a tubular portion and a foot, a member mounted in said tubular portion for reciprocation, a needle holder pivoted to said member, a spring movable with said member acting to swing said holder about its pivot and an adjusting screw threaded in said member and engaging said 130

needle holder to limit its swinging motion about its pivot under the action of said spring, said frame having an opening in the side thereof and said screw extending 5 into said opening.

5. In a hand embroidering machine, a frame comprising a tubular portion having a foot, a hollow member reciprocable in said frame, a bar slideable within said member 10 and having a portion for engagement with one end of said member and a thread gripping member for engagement with the other end of said member, a needle holder pivoted to said member, a spring movable with 15 said member and tending to swing said holder on its pivot and an adjusting screw threaded through said member and engaging said holder to adjustably limit the swinging of the holder under the action of said 20 spring.

6. A hand embroidering machine of the character described including a frame comprising a hollow frame member and a foot removably connected therewith and having 25 an opening therethrough whereby said frame is provided with an aperture, a reciprocating member fitted into said frame member and having a plurality of apertures therein in line with the aperture in said 30 frame, a needle carrying holder pivotally mounted on said reciprocating member, a

screw extending loosely through one of the apertures in the reciprocating member and into the holder, a spring contacting on said reciprocating member and the head of said 35 screw so as to urge the holder connected therewith to rotate on its pivotal mounting, a second screw threaded into the second aperture in said reciprocating member, said second screw bearing against one end of the 40 holder for moving the holder against the action of said spring, a reciprocating part mounted in said reciprocating member, a thread tension and guiding member connected with said part and means carried 45 by said frame for supporting a supply of thread.

7. In a hand embroidering machine, a frame comprising a tubular portion and a foot, a member mounted in said tubular portion for reciprocation, a needle holder pivoted to said member, a spring movable with 50 said member acting to swing said holder about its pivot, means for holding a needle in said holder, and an adjusting screw 55 threaded in said member and engaging said needle holder to limit its swinging motion about its pivot under the action of said spring, said frame having an opening in the side thereof and said screw and means extending into said opening.

WILLIAM COHEN.
